COUNTERTOP RANGE

George W. Kamin, Arcadia, Calif., assignor to Pan-Pacific Manufacturing Corp., Los Angeles, Calif., a corporation of California

Filed Feb. 1, 1960, Ser. No. 59,225

Term of patent 7 years

(Cl. D81—25)

Figure 1 is a front perspective view of a countertop range embodying the design;

Figure 2 is a side elevational view thereof;

Figure 3 is a fragmentary top plan view, showing the front portion of the countertop range; and

Figure 4 is a front elevational view thereof.

I claim:

The ornamental design for a countertop range, substantially as shown.
